HALF-SOLING PINCERS AND NAILER

Guiseppe Ferrini, Bozeman, Mont.

Application May 29, 1935, Serial No. 24,121

4 Claims. (Cl. 1—46)

This invention relates to a tool particularly adapted to secure one leather piece to another leather piece and for instance to the attachment of half-soles of shoes to the shanks thereof in a manner which substantially conceals the joint.

The specific objects and advantages will become apparent from a consideration of the description following taken in connection with accompanying drawings illustrating an operative embodiment.

In said drawings:—

Figure 1 is a view in side elevation of the improved tool showing all of the parts in spaced relation;

Figure 2 is a plan view of the tool of Figure 1;

Figure 3 is a view substantially similar to Figure 1 showing many of the parts in cross section;

Figure 4 is a detail section taken on the line 4—4 of Figure 1;

Figure 5 is a horizontal section taken on the line 5—5 of Figure 1;

Figure 6 is a view primarily in elevation showing the tool in use;

Figure 7 is a fragmentary view substantially similar to Figure 6, showing the tool in use in a different position;

Figure 8 is a detail section taken substantially on the line 8—8 of Figure 7, and

Figure 9 is a plan view of one of the tacks or nails employed.

Referring specifically to the drawings wherein like reference characters designate like or similar parts, 10 and 11 are a pair of levers pivoted together at 12 by means of a bolt or in any other suitable manner and respectively having handles 13 and 14. Said levers also respectively have jaws at 15 and 16, preferably beveled as shown, since they are adapted to enter channels in leather elements 18 and 19 and draw such elements together.

Said jaws 15 and 16 are normally separated due to the provision of a leaf spring 20 engaging both of the levers 10 and 11 and fastened to one of them as at 21.

45 A third lever is employed at 22, being pivoted by a bolt or otherwise at 23 through the lever 10, its free end terminating short of the free ends of the handles 13 and 14, and having a depending actuator element 24, which is pivoted thereto as at 25 and passes through a suitably enlarged slot 26 in the handle 13. In the opposite end of the lever 22, a rod 27 is slidable in a recess 28, and it has a hammer rod 29 transversely pivoted thereto at 30. Said rod 29 extends into and is slidable 50 through a vertical slot 31 extending completely

through the jaw 16 adjacent its free end. Said hammer rod 29 and end of lever 22 adjacent the same are normally urged into uppermost or retracted position through the medium of an expansive spring 32 engaging sockets at 33 and 34, 5 respectively, provided in the jaw 16 and lever 22.

Extending longitudinally of the jaw 11 and open at one side thereof is a magazine or slot 35 containing a plurality of nails or tacks 36 whose heads are in abutment and are substantially rectangular 10 as suggested in Figures 5 and 9. Said nails or tacks 36 are urged by a follower 37 and an expansive spring 38 to the left so that when the hammer rod 29 is retracted, one of the tacks will be urged into the slot or passageway 31. A plate 15 39 is detachably secured over the magazine 35 and slot 31 by means of screws or the like 40 engaging threaded openings in the jaw 11. Anvil projections 41 are preferably provided in alignment, one on each jaw 15 and 16. 20

Reverting to the leather pieces 18 and 19 the former may represent the shank of a shoe and the latter represents a half-sole being applied thereto in the process of repairing or half-soling a shoe. The joint, that is, the channel or slotted sides of 25 the leather 18 and 19 will be uppermost in the shoe and hence concealed. Obviously the invention is not limited to use in such connection.

Presuming use, the handles 13 and 14, with the jaws 15 and 16 engaged in channels in the leather 30 members 18 and 19, are pressed toward each other and the leather members drawn into tight engagement as shown in Figures 6 and 8, subsequent to which, a finger or fingers is engaged with the actuator 24 and the latter moved upwardly, there- 35 by swinging the lever 22 and causing the hammer rod 29 to descend, driving the nail or tack 36 in its path through the leather as shown in Figure 6. After this action the tool is moved slightly forward so that the anvil projections 41 40 respectively engage the head and point of the nail or tack as shown in Figure 7 and subsequent pressure on the handles 13 and 14 to move them toward each other will upset the point of the nail or tack. 45

Due to the pivotal and sliding connection as at 30 and 27, for the hammer bar or rod 29, the latter may move at a right angle to the jaw 16 without any binding action of the parts.

Various changes may be resorted to provided 50 they fall within the spirit and scope of the invention.

What is claimed is:—

1. A tool of the class described comprising lever members pivotally connected together, said lever 55

- members having opposed jaws, one of said jaws having a magazine for nails, a passageway in the jaw for the nails, means urging the nails toward the passageway, a hammer rod movable in said passageway, a lever pivoted to one of the first mentioned levers, a connection between said hammer rod and last mentioned lever, and an element operable to move the last mentioned lever relatively to the first mentioned levers, said connection comprising a rod slidably mounted substantially longitudinally of the last mentioned lever, and said hammer rod being pivoted thereto.
2. A tool of the class described comprising lever members pivotally connected together, said lever members having opposed jaws, one of said jaws having a magazine for nails, a passageway in the jaw for the nails, means urging the nails toward the passageway, a hammer rod movable in said passageway, a lever pivoted to one of the first mentioned levers, a connection between said hammer rod and last mentioned lever, and an element operable to move the last mentioned lever relatively to the first mentioned levers, each jaw having an anvil projection thereon, said anvil projections being substantially aligned with each other.
3. A tool of the class described comprising lever members pivotally connected together, said lever members having opposed jaws, one of said jaws having a magazine for nails, a passageway in the

jaw for the nails, means urging the nails toward the passageway, a hammer rod movable in said passageway, a lever pivoted to one of the first mentioned levers, a connection between said hammer rod and last mentioned lever, said connection comprising a rod slidably mounted substantially longitudinally of the last mentioned lever, said hammer rod being pivoted thereto, and a depending actuator pivoted to the last mentioned lever and extending through and below a slot in the handle of one of the first mentioned levers.

4. A tool of the class described comprising lever members pivotally connected together, said lever members having opposed jaws, one of said jaws having a magazine for nails, a passageway in the jaw for the nails, means urging the nails toward the passageway, a hammer rod movable in said passageway, a lever pivoted to one of the first mentioned levers, a connection between said hammer rod and last mentioned lever, said connection comprising a rod slidably mounted substantially longitudinally of the last mentioned lever, said hammer rod being pivoted thereto, a depending actuator pivoted to the last mentioned lever and extending through and below a slot in the handle of one of the first mentioned levers, spring means to urge the first mentioned levers apart, and spring means to urge the third mentioned lever away from the other levers.

GUISEPPE FERRINI. 36
